SIGMUND L. GOLDMAN, OF CHICAGO, ILLINOIS, ASSIGNOR TO E. GOLDMAN & CO. INC., OF CHICAGO, ILLINOIS, A CORPORATION OF ILLINOIS.

BALL-BEARING FOR CONVEYER-ROLLERS.

No. 914,714.

Specification of Letters Patent.

Patented March 9, 1909.

Application filed May 11, 1908. Serial No. 432,260.

To all whom it may concern:

Be it known that I, SIGMUND L. GOLDMAN, a citizen of the United States, residing at Chicago, in the county of Cook and State of Illinois, have invented a new and useful Improvement in Ball-Bearings for Conveyer-Rollers, of which the following is a specification.

My invention relates to an improvement in the class of ball-bearing rollers, used more especially in gravity conveyers.

In the accompanying drawing, Figure 1 is a broken longitudinal section of a conveyer-roller embodying a desirable form of my improvement, and Fig. 2, a similar view 15 of the same showing a modification.

The hollow metal cylinder 3, which forms the body of the roller, and is preferably composed of seamless tubing, is provided in each end with a roller-bearing. In this 20 roller-bearing the cup 4 is formed of an outer annular cupped section 5 provided with a circumferential flange 6 about its outer edge, and an inner annular cupped section 7 provided with a circumferential flange 8 about its outer edge. The section 5 is formed of spring-metal, preferably sheet-steel, and the section 7 is formed of the same metal but is case-hardened to enable it to withstand the wear of the balls 9, whereby, 30 however, it is deprived of its springy quality. The sleeve 10, which is preferably formed of the same metal as the cup-sections and is also case-hardened, is expanded between its ends into a circumferential flange 35 11 of approximately V-shape in cross-section to form the cone for confining the balls in the race 12, and the outward extension 13, the latter serving the spacing purpose hereinafter explained. The inner cup-section is 40 covered with an annular metal disk 14 which is secured in place preferably by spinning its circumferential edge into a dovetail-groove 15 formed about the edge of that cup-section.

To secure a ball-bearing in an end of the cylinder 3 it is pressed into that end until the flange 6 abuts against the extremity of the cylinder, such pressing into place of the cup serving to hold it in position by reason 50 of the springy quality of the section 5 binding it by its expansion against the inner wall of the tube. With a roller-bearing thus secured in each end of the roller-tube, the shaft 16, the diameter of which is such 55 as to render it a tight fit in the alining

sleeves 10 of the two bearings, is driven through them from either end of the cylinder (preferably with the latter supported vertically on end), and thereby rigidly and non-rotatably fastened centrally within the 60 same. The projecting ends of the shaft are fastened stationarily in the sides 17, 17 of the frame of the conveyer-device in which the rollers are employed, and in that position the outer ends of the sleeve-extensions 65 13 bear against the frame-sides, thereby spacing them from the cylinder-ends.

The modification of the device illustrated in Fig. 2 consists in extending the circular flange 6 into an outwardly flaring flange 66 70 to project from the cylinder-ends and afford confining guides for packages moving on the rollers of the conveyer, tending to maintain the packages in their course. The extent of projection of flange 66 necessitates 75 the greater length illustrated of the sleeve-extension 13 than that shown in Fig. 1, to project it for its spacing purpose against the respective frame-side 17.

The purpose of the essential sectional construction of the cup 4 is to enable it to be pressed into the cylinder-end to secure it in place. Where, as hitherto, this cup has been formed of a single piece, this manner of fastening, which is mechanically the best, is 85 not possible because of the necessity for case-hardening the ball-race portion, which is not practical without case-hardening the entire cup, whereby it is deprived of the springy quality necessary for enabling it to 90 be pressed into place for securing it therein.

My improved construction presents the further advantage of requiring no adjusting to relieve the balls from binding. The parts, which may be first assembled and then introduced into the tube, or assembled in the act of so introducing them in the order of the outer cup-section, the inner cup-section, the balls, the sleeve and the disk-cover, are formed to confine the balls in their races in 100 a manner to permit them to turn freely. This condition is not impaired by driving the shaft into place from either end of the tube 3, because the flanges 6 and 8 at one end (the upper one with the tube supported 105 in vertical position for the shaft-driving operation, with the disk-cover in its opposite end bearing against the object on which the tube is so supported) prevent the strain of driving the shaft from disturbing the rela- 110

tive positions of the ball-embracing parts, and the disk-cover at the then lower end of the tube affords a stop against displacement of the inner cup-section. It will furthermore be observed that a ball-bearing may be removed, for any purpose, from the tube without disorganizing the bearing.

I claim:

1. In combination, a tubular roller, ball-bearings in the roller-ends, each comprising a cup composed of an outer annular section of spring metal a separate annular section within said outer section and forming the ball-race, balls in said race, a cone-forming sleeve confining the balls therein, and a shaft extending in the roller through the roller-bearing sleeves, for the purpose set forth.

2. In combination, a tubular roller, ball-bearings in the roller-ends, each comprising a cup composed of an outer annular cupped section of spring metal, a separate annular cupped section within said outer section and forming the ball-race, balls in said race, a sleeve forming the ball-confining cone, and a shaft extending in the roller through the roller-bearing sleeves, for the purpose set forth.

3. In combination, a tubular roller, ball-bearings in the roller-ends, each comprising a cup composed of an outer annular cupped section of spring-metal frictionally engaging the inner wall of the respective roller-end and provided with a flange abutting against said end, a separate annular cupped section of non-resilient metal forming the ball-race within said outer section and provided with a flange abutting against the same, a cone-forming sleeve confining the balls in the race, and a shaft extending in the roller through the roller-bearing sleeves, for the purpose set forth.

4. In combination, a tubular roller, ball-bearings in the roller-ends, each comprising a cup composed of an outer annular cupped section of spring metal provided with a flange abutting against the respective roller end, a separate annular cupped section, forming the ball-race within said outer section and provided with a flange abutting against the same, balls in said race, an an-

nular cover fitting said inner section and a cone forming sleeve extending through said cover and confining the balls in said race, and a shaft extending in the roller through the roller-bearing sleeves, for the purpose set forth.

5. In combination, a tubular roller, ball-bearings in the roller-ends, each comprising a cup composed of an outer section of spring metal provided with an outwardly projecting package-guiding circumferential flange, a separate annular cupped section within said outer section and forming the ball-race, balls in said race, a sleeve having an enlargement to form the ball-confining cone, and a shaft extending in the roller through the roller-bearing sleeves, for the purpose set forth.

6. In combination, a tubular roller, ball-bearings in the roller-ends, each comprising a cup composed of an outer annular section of spring metal, a separate annular section within said outer section and forming a ball-race, balls in said race, a sleeve having an enlargement between its ends to form a ball-confining cone, and extended at its outer end beyond the roller for the described spacing-purpose, and a shaft extending in the roller through and beyond the roller-bearing sleeves.

7. The combination, for the purpose set forth, of a tubular roller, ball-bearings in the roller-ends, each comprising a cup composed of an outer annular cupped section of spring metal provided with a flange abutting against the respective roller-end, a separate annular cupped section forming the ball-race within said outer section and provided with a flange abutting against the same, a sleeve having an enlargement between its ends to form the ball-confining cone and extended at its outer end beyond the roller for the described spacing-purpose, and a shaft extending in the roller through and beyond the roller-bearing sleeves.

SIGMUND L. GOLDMAN.
